BOTTLE CLOSURE

Henry O. Magnuson, Chicago, Ill., assignor to
 Champion Foundry & Machine Co., Chicago,
 Ill., a corporation of Illinois

Application April 11, 1934, Serial No. 719,989

5 Claims. (Cl. 215—52)

This invention relates to bottle closures, and has reference more particularly to closures of the composite expanding stopper type. One object of the invention is to provide a very simple, inexpensive, and efficient bottle closure, and one that can be easily manipulated for applying and removing it, and that, when entered in the neck of a bottle, will be self-sealing. Another object is to provide an improved closure of the type specified of such a structure that its removal will not involve any mutilation or destruction of its parts, so that it may be re-used many times.

One practical embodiment of the invention is illustrated in the accompanying drawing, in which—

Fig. 1 is a view partly in elevation and partly in vertical section, showing the manner of entering the stopper into a bottle neck.

Fig. 2 is a vertical section, showing the stopper expanded to sealing position in the bottle neck.

Fig. 3 is an elevation of the closure in the normal position of the parts when out of the bottle neck.

Referring to the drawing, B designates the body and N the neck of a common form of bottle such as is used for bottling beer, ginger ale, and other like beverages.

My improved closure is of the composite expanding stopper type. 10 designates a hollow rubber stopper, the widened upper end 11 of which is formed with an integral inwardly directed annular flange 12 that enters a peripheral groove 13 formed in a rigid head member 14 of wood or other suitable material, whereby the stopper and head are interlocked. The head 14 has a central bore 15 that forms a lateral support and guide for a slideable plunger 16 that is equipped with a knob or button 16' on its upper end for depressing it by the thumb in the manner indicated in Fig. 1. The stopper 10 has a closed lower end 10'; and on the internal wall of the stopper, slightly above its lower end, is an annular rib 17. The plunger 16 extends downwardly into the hollow stopper 10, and its lower end portion is formed with an annular cam 18 that cooperates with the rib 17 to expand the stopper in the manner later described. Preferably the upper portion of the body of the stopper is tapered, as shown at 19, to fit a correspondingly tapered seat 20 in the upper end of the bottle neck, although this is not essential to the proper functioning of the device.

To connect the head 14 to the top of the stopper, the flexible and stretchable flange 12 is first spread outwardly and downwardly as shown by

dotted lines in Fig. 2, and then turned inwardly and entered into the groove 13 of the head. Preferably cement is applied to the flange before it is entered into the groove to form a more perfect bond.

In applying the closure to a bottle, the closure is grasped by the thumb and fingers, and the stopper 10 is first stretched and elongated by pressing down on the head 16' of the plunger. The body of the stopper is then inserted in the neck of the bottle and pressed downwardly to create a tight fit of its tapered portion 19 with the tapered seat 20 in the upper end of the bottle neck, as shown in Fig. 1. The body of the stopper readily enters the bottle neck by reason of the fact that the stretching of the stopper reduces its normal width, as shown by comparing Fig. 1 with Fig. 2. This stretching carries the plunger cam 18 below the rib 17, as shown in Fig. 1. The operator then releases the down pressure on the plunger, and the endwise contraction of the stopper raises the plunger and causes the cam 18 to pass through the annular rib 17, thus expanding the lower portion of the stopper into tight sealing engagement with the internal wall 25 of the bottle neck, all as shown in Fig. 2. The closure may readily be withdrawn by merely grasping it and depressing the plunger, as shown in Fig. 1, and then lifting it out.

It will thus be seen that in its sealing action the device is entirely automatic or self-sealing, and does not require the use of any manually operated cams or other spreaders to expand the stopper into sealing engagement with the bottle neck. Moreover, the withdrawal of the closure does not involve any mutilation or destruction of any of its parts, so that it can be reused many times, so long as the rubber stopper element retains its elasticity, which conduces greatly to economy.

While I have, for the purposes of illustration, shown and described one practical form in which the principle of the invention may be embodied, it is manifest that the structural details may be changed without involving any departure from the operative principle or sacrificing any of the advantages inherent in the invention. Hence, I reserve all such variations, modifications and mechanical equivalents as fall within the scope and purview of the appended claims.

I claim:

1. In a bottle closure of the composite expanding stopper type, the combination with a hollow rubber stopper adapted to enter the neck of a bottle and formed with a closed lower end,

of a plunger movable endwise within said stopper to stretch the latter endwise through contact of its lower end with the closed lower end of the stopper, and cooperating means on said stopper and plunger operating to automatically expand the stopper into sealing engagement with the internal wall of the bottle neck under endwise contraction of the stretched stopper.

2. In a bottle closure of the composite expanding stopper type, the combination with a hollow rubber stopper adapted to enter the neck of a bottle and formed with a closed lower end, of a plunger movable endwise within said stopper to stretch the latter endwise through contact of its lower end with the closed lower end of the stopper, an internal rib on said stopper, and a cam on said plunger cooperating with said rib to automatically expand the stopper into sealing engagement with the internal wall of the bottle neck under endwise contraction of the stretched stopper.

3. In a bottle closure of the composite expanding stopper type, the combination with a hollow rubber stopper adapted to enter the neck of a bottle and formed with a closed lower end, of a centrally bored head secured to the upper end of said stopper, a plunger guided in the bore of said head and movable endwise within said stopper to stretch the latter endwise through contact of its lower end with the closed lower end of the stopper, an internal annular rib on said stopper

slightly above the closed lower end of the latter, and an annular cam on the lower portion of said plunger cooperating with said rib to automatically expand the stopper into sealing engagement with the internal wall of the bottle neck under endwise contraction of the stretched stopper. 5

4. A bottle closure comprising a hollow, elastic rubber stopper, and a plunger in the stopper and engaging its lower end and adapted to be depressed to stretch the stopper lengthwise, the stopper and plunger having cooperating parts fixed respectively thereto and normally engaged to expand the stopper, said stopper and plunger parts being movable out of cooperative relation as the plunger is depressed to stretch the stopper and re-engage to re-expand the stopper as the plunger is retracted by the lengthwise contraction of the stretched stopper. 10 15

5. A bottle closure comprising a hollow, elastic rubber stopper having an internal rib spaced above its lower end, and a plunger within the stopper, engaging its lower end and having an enlargement normally engaging said rib to expand the stopper, said plunger being depressible to stretch the stopper lengthwise and move its enlargement to a position below said rib, and said enlargement being re-engaged with the rib to re-expand the stopper as the plunger is retracted by the lengthwise contraction of the stretched stopper. 20 25 30

HENRY O. MAGNUSON.
